CLAIM

The ornamental design for a “plastic container,” as shown and described.

DESCRIPTION

FIG. 1 is a perspective view showing my new design;
 FIG. 2 is a first side elevational view;
 FIG. 3 is a second side elevational view;
 FIG. 4 is a front elevational view;
 FIG. 5 is a rear elevational view;
 FIG. 6 is a top plan view; and,
 FIG. 7 is a bottom plan view.

It is certified that error appears in the above-identified patent and that said Letters Patent is hereby corrected as shown below:

Title page illustrating a figure should be deleted, and replace with a new title page illustrating a figure. (Attached)

Title page.

Item [62], **Related U.S. Application Data**, insert -- **Cross Reference to Related Applications**

This application is related to U.S. Serial No. 29/079,317, filed November 12, 1997; U.S. Serial No. 29/079,318, filed November 12, 1997; and U.S. Serial No. 29/079,350, filed November 12, 1997. --.

Drawings.

Delete drawing sheets 1-4, and substitute therefor drawing sheets 1-4, (Attached)

Signed and Sealed this

Twenty-second Day of March, 2005

A handwritten signature in black ink, appearing to read "Jon W. Dudas", is centered within a dotted rectangular box.
